UNITED STATES PATENT OFFICE

LEIF LEE, OF YOUNGSTOWN, OHIO

FURNACE

Application filed February 23, 1933. Serial No. 341,919.

My invention relates to furnaces and more particularly to furnaces for transferring heat between two moving columns of fluid.

In heating moving columns of fluid by the products of combustion from a furnace, it has heretofore been customary to pass the products of combustion through one or more passageways defined by walls of ceramic material. The fluid being heated traverses one or more passageways in heat transferring engagement with the ceramic material defining the passageway or passageways traversed by the products of combustion. Heat from the products of combustion is transferred to the fluid being heated by the ceramic material. Difficulty has heretofore been experienced in preventing the transfer of small bodies of fluid through the joints in the ceramic walls, which leakage is liable to render the fluid being heated unfit for its intended use. This is especially true where the heated fluid is air for heating a building.

Where the products of combustion from a furnace are permitted to move upwardly through passageways by reason of the differences in the specific gravity of the heated products of combustion and the cold air entering the furnace, there is a tendency for the escaping products of combustion to move upwardly without bringing all of the products of combustion into engagement with the walls for absorbing heat from them. Furnaces have also been constructed in which a condition of forced or induced draft existed by connecting the passageways with blowers. Under such conditions when the blower is rendered inoperative from any cause, difficulty has frequently been experienced in securing a circulation of the fluids through the passageways normally controlled by the blowers or fans.

I provide a furnace having passageways for products of combustion moving from a furnace to a stack in heat exchanging relation to passageways conducting a fluid, such as air, which is to be heated. Provision is made for insuring a uniform flow of fluids through the respective passageways by connecting them to a blower or a fan. To prevent leakage between the respective passageways,

I utilize metallic sheets. Where the products of combustion engaging the sheets are at high temperature, the sheets are protected by a covering of ceramic material. Where the products of combustion are at a lower temperature, the metallic sheets are directly exposed to the products of combustion and the fluid being heated. By the use of sheets leakage between the passageways for the fluids of different characteristics is prevented. Such a leakage is very apt to occur through the joints between the ceramic blocks usually used for covering such passageways.

By causing the products of combustion to move through successive passageways with a downward movement against their natural tendency to rise, the products of combustion are maintained under a condition of pressure which packs them and brings substantially the entire volume of the products of combustion into engagement with the heat exchange walls separating the passageways. Provision is made for securing movement of the fluids through the passageways when fans or blowers are rendered inoperative from any source.

By utilizing sheet metal plates as barrier walls between the passageways for the different fluids, I am able to fabricate the passageways by welding cross pieces between sheets in situ. By providing openings in the sheets in line with the surfaces which are to be welded thereto, I am able to weld the adjacent metal bodies together by passing welding material through the openings and forming a bead between the walls of the openings and the face of an adjacent metallic body.

The accompanying drawings illustrate the present preferred embodiment of the invention in which:

Figure 1 is a longitudinal sectional view of a furnace embodying my invention;

Figure 2 is a plan view in section of the furnace taken substantially along the section line II-II of Figure 1;

Figure 3 is a transverse sectional view taken along the section line III-III of Figure 1; and

Figure 4 is a perspective view of a detail of the invention.

Referring to the drawings, a furnace 2 is supported by beams 3 and 4 spanning a masonry pit 5. The beams 3 and 4 are seated in the side walls of the pit 5. The beams 3 support a bed plate 6 on which side walls 7 and a rear wall 8 of a combustion chamber 9 rest. The front wall of the combustion chamber 9 is provided with a door 10 through which fuel may be supplied. Grates 11 are mounted in the combustion chamber 9. A door 12 is provided near the bottom of the combustion chamber for the admission of draft air and for the removal of ashes.

The outer surfaces of the combustion chamber are lined by a side plate 14 and end plates 15 and 16. A plate 17 is spaced from the plate 14 by the ends of the plates 15 and 16 and a beam 18 for constituting vertically extending passageways along the outer surface of the combustion chamber. The plates 14 and 15 are connected by an angle bar 19 welded thereto. A similar angle bar 20 connects the plates 14 and 16. An angle bar 21 connects the plates 16 and 17. A crimp 22 is provided at one end of the plate 17 to provide a surface for welding it to the plate 15.

As shown in Figure 1, the passageways between the plates 14 and 17 are open to the pit at their lower ends and are open to a hood 24 at their upper ends. Accordingly, a circulation of air past the outer end of the furnace utilizes the heat normally radiated from that surface. The products of combustion from the chamber 9 pass into a heat transfer chamber 25 through a series of openings 26.

The heat transfer chamber 25 is supported by the beams 3 and 4 between which a bed plate 27 is suspended by angle irons 28 and 29 welded to the beams 3 and 4 respectively. The outer wall 30 of the heat transfer chamber 25 is constituted by a masonry structure and a surface plate 31. The surface plate 31 is provided with a plurality of openings 32 and covers 33. The openings 32 are in alignment with openings 34 through the masonry wall, which openings communicate with passageways formed within the heat transfer chamber.

The side walls of the heat transfer chamber 25 are formed by vertically extending plates 35 extending between a pair of vertically extending beams 36 secured to the beam 3 and vertically extending angle irons 37 supported by a perforated beam 38. Outside the plates 35, parallel extending plates 39 and vertically extending angle bars 40 define passageways 41 through which fluid being heated moves upward to utilize the heat radiated from the side walls of the heat transfer chamber 25. The interior of the heat transfer chamber 25 is sub-divided into a number of groups of horizontally extending passageways 42, 43 and 44 through which the products of combustion pass from the open-

ings 26 to a discharge duct 45 in which the perforated beam 38 is mounted.

Vertically extending passageways 46 for the passage of fluid to be heated are disposed between the groups of horizontally extending passageways 42, 43 and 44. The passageways 46 are defined by vertically extending metallic sheets 47. The sheets 47 are closed at their ends by cross pieces 48 to constitute the passageways 46. The passageways 46 terminate at their lower ends in openings 27a formed in the bed plate 27. At their upper ends the passageways 46 open into the hood 24. Accordingly, fluid, such as air rises, from the pit through the passageways 46 and after being heated is discharged into the hood 24.

Leakage of the products of combustion from the passageways 42, 43 and 44 into the passageways 46 is prevented by the presence of the sheets 47 and the cross pieces 48 which make tight joints. Where masonry walls alone are relied on for defining heat transfer passageways, leakage of the products of combustion into the fluid being heated frequently takes place between the joints of the ceramic bodies constituting the walls of the passageways.

The passageways 42, 43 and 44 are defined by baffles 49 extending between pairs of plates 47. The pairs of plates connected by the baffles 49 alternate with the pairs connected by the cross pieces 48, so that the passages for the products of combustion and the fluid being heated alternate. The baffles 49 are supported by angle irons 50 secured to the plates 47. Preferably the angle irons are welded to the plates, although it is to be understood that they may be secured by rivets or the like if desired. To protect the plates 47 from the hottest products of combustion when leaving the openings 26, the passageways 42 are provided with linings 51 of ceramic blocks. The lower passages 43 and 44 where the products of combustion are cooler need not be provided with ceramic linings. By utilizing relatively thin metal plates through which the heat transfer takes place, instead of thick ceramic walls heretofore generally used in transfer chambers of this general character, I am able to obtain a much greater heat transfer at low temperatures than has heretofore been possible.

The passageways 42 and 43 are connected at the outer end of the transfer chamber by omitting portions of the baffles 49. The passageways 43 and 44 are similarly connected at the inner end of the chamber. The passageways 44 are connected through an opening 52 to the duct 45.

Downward circulation of the products of combustion through the passageways 42, 43 and 44 is obtained by connecting the duct 45 to a fan or blower 54 through which the products of combustion pass in moving to an out-

let stack 55. By causing a downward circulation of the products of combustion through the heat transfer chamber 25 against the natural tendency to rise, the products of combustion are kept under pressure and packed which causes substantially their total volume to engage the side walls of the passageways 42 and 43, thereby giving off the heat carried by them before entering the duct 45. In the event of the failure of the blower 54, a natural circulation of the products of combustion is obtained by opening a valve 56 connecting the duct 45 and stack 55, thereby shunting the fan 54.

Air or other fluid being heated is supplied to the pit beneath the passageways 46 by a fan or blower 57 through a duct 58. The blowers 54 and 57 are preferably driven from a single motor 68 although it is to be understood that they may be separately driven if desired.

For insuring a supply of air in the event of the failure of the blower 57, the outer end of the pit is closed by a series of vertical plates 59 which may be opened, thereby providing a natural circulation of air through the passageways 46.

Referring to Figure 4, I have provided a method of welding the plates and cross members in situ. Plates 60 and 61 to be connected are provided with a series of holes 62 and 63, respectively, near their areas of engagement. An angle bar 64 is placed in engagement with the openings 62 and 63. Thereafter beads of welding material 65 are disposed in the opening. The beads 65 unite the plates 60 and 61.

This same construction is adapted equally well to the securing of the cross pieces 48 in position between adjacent sheets 47. In such case, the cross pieces 48 may be constructed in the form of channel bars or I-beams secured in position by welding through the medium of openings and beads of welding material in the manner before referred to.

While I have shown the present preferred embodiment of the invention, it is to be understood that it may be otherwise embodied within the spirit of the invention and the scope of the appended claims.

I claim:

1. In a furnace, an air heating system comprising a plurality of vertical parallel spaced metal plates alternately separated by spaced vertical and spaced horizontal metal plates secured thereto, said horizontal plates being staggered and providing a tortuous passage for combustion gas, means whereby a stream of air is introduced to the bottom of the vertical passages formed by the spaced vertical metal plates, and means whereby a stream of hot combustion gas is introduced to the top passages formed by the spaced horizontal plates.

2. In a furnace, the combination with a

plurality of vertical parallel spaced flat rectangular metal plates, parallel spaced vertical and spaced parallel horizontal metal plates alternately separating said first plates and welded thereto by means of substantially gas tight connections, said horizontal plates being staggered and providing a tortuous passage for combustion gas, means whereby a stream of fluid at one temperature is introduced to the top inlets of the horizontal passages and means whereby a stream of fluid at another temperature is introduced to the bottom inlets of the vertical passages.

3. In a furnace, an air heating system comprising a plurality of parallel spaced vertical hollow metal partitions having vertical air passages of rectangular section extending therethrough from the top to the bottom of the partition, spaced horizontal metal baffle plates disposed between said partitions said baffle plates being arranged to provide downwardly winding passages for the hot combustion gases between the hollow partitions, said air and gas passages being air and gas tight with respect to each other, means whereby air may be introduced to the bottom of the air passages through the partitions where it is caused to come into contact with hot areas of gradually increasing temperatures as it ascends to the top of the partitions, the increased heat areas being effected by the hot combustion gases being initially introduced at the top of the gas passages and thence moved downwardly by a winding route through the horizontal passages to the bottom of the partitions, blowers for normally circulating the combustion gases and the air in proper directions, means whereby air may be admitted to the air passages exclusive of the air blower, and means whereby the hot gases may be circulated in the proper direction exclusive of the gas blower.

In testimony whereof I have hereunto set my hand.

LEIF LEE.
